UNITED STATES PATENT OFFICE.

ELMER J. BLISS, OF BOSTON, MASSACHUSETTS.

INSIDE GAGE FOR FITTING SHOES.

1,317,681.

Specification of Letters Patent.

Patented Oct. 7, 1919.

Application filed September 10, 1917. Serial No. 190,453.

To all whom it may concern:

Be it known that I, ELMER J. BLISS, citizen of the United States, and resident of Boston, Massachusetts, have invented certain new and useful Improvements in Inside Gages for Fitting Shoes, of which the following is a specification.

This invention relates to the fitting of shoes and is intended to provide a gage adapted to lie between the bottom of the foot and the inside surface of the shoe bottom for the purpose of accurately gaging the length of the foot in comparison with the length of the shoe while the shoe is actually on the foot, and the weight of the person being measured rests normally on the foot.

It is common knowledge that injuries to the foot, such as ingrowing toe-nails, large joints and other troubles are very frequent occurrences due to the fact that too short shoes are selected. Other troubles such as fallen arches, etc., are due to the selection of shoes that are too long for the wearer.

Now when a person tries on an ordinary shoe the stiff box in the toe makes it impossible to tell accurately just where the end of the great toe lies inside of the shoe. Heretofore the attempt to select a proper fit has been largely a matter of guess-work supplemented by more or less unreliable judgment. The usual measuring or size stick is apt to be misleading because different feet will spread or lengthen different degrees according to the shape and build of the particular foot. To overcome these difficulties and afford a reliable and certain means for ascertaining whether a particular size shoe is the proper size for the person trying it on, I have devised a special gage comprising essentially a thin flat longitudinal member adapted to lie between the bottom of the foot and the inside of the shoe bottom or insole without interfering with the proper fitting of the shoe, and adapted to permit the weight of the wearer to rest thereon in a natural manner.

The particular construction thereof and the mode of its use will be hereinafter explained and the characteristic novelty thereof will be defined in the claims hereto annexed.

In the accompanying drawings I have illustrated a simple and convenient form embodying the principles of this invention 55 in which,

Figure 1 is a side elevation illustrating the relation of the interior gage to the foot and to the shoe, respectively;

Fig. 2 is a plan view illustrating the position of the gage in the shoe;

Fig. 3 is a perspective view of the interior gage removed from the shoe.

In the practice of the invention according to the form illustrated, I employ an elongated thin flat strip *a* of a somewhat flexible material of a length corresponding to a particular size of shoe and adapted to lie flat on the inside surface of the shoe bottom so as not to appreciably raise the foot in the shoe or cause discomfort when the weight of the wearer rests thereon.

To the forward end of the longitudinal member is secured a small spacing member which is here shown as a wooden or metal block whose forward surface is suitably curved to fit into the extreme toe portion of the shoe upper and whose rear portion or face extends transversely of the longitudinal member *a* preferably as a flat or plane surface.

This spacing or toe-member *b* may be secured to the longitudinal member in any suitable manner but I prefer to make the connection a detachable one by the use of screws *b'* or other suitable attaching means in order to permit the substitution of spacing toe members of different shape or thickness if desired.

Ordinarily in fitting a person with a round or broad toe shoe, such for example as army shoes, it is customary to add two sizes to the actual length measure of the foot indicated by the usual size stick but this rule is only an approximation and does not apply to all shapes of feet. Suppose, therefore, that the size stick indicates a foot size of $8\frac{1}{2}$ then the salesman would naturally select a $10\frac{1}{2}$ shoe for the foot. Before trying on the $10\frac{1}{2}$ shoe, however, the size $10\frac{1}{2}$ interior gage will be inserted in the shoe as indicated in the drawings. The length of the interior gage member should be such as to fit snugly between the heel and toe portions of the shoe so as to prevent longitudinal slip or displacement. Ordinarily for this type of shoe the toe or spacing member *b* will have a thickness from rear to front corresponding to one size of a shoe, namely, about $5/16$ of an inch. If the shoe has a pointed toe, however, a thicker spacing

member or toe block should be used running from $1\frac{1}{2}$ to possibly 2 sizes in thickness according to the shape of the toe.

When the proper gage has been inserted in the shoe, the person being fitted puts on the shoe and rests his weight thereon in a normal manner so as to allow the foot to expand and lengthen. In this position the extreme end of the great toe should slightly 5 graze the rear or transverse face of the toe block. If the toe cannot touch the block at all the shoe is too long. If the toe presses strongly against the block, the shoe is too short. It will, of course, be understood that 10 different length gages must be used for different sized shoes, each gage corresponding to the interior length of the shoe.

The above described devices form a means for perfectly and reliably ascertaining the correct location of the end of the toe 20 in the shoe and when used as described forms a means of preventing the selection of either too short or too long a shoe which have caused so much injury and trouble.

25 What I claim is:

1. An interior gage for fitting shoes embracing a flat member adapted to lie longitudinally between the bottom of the foot and the insole of the shoe, and a toe gaging 30 member secured to the forward end of said longitudinal member and extending transversely of the longitudinal member in position to form a contact with the extreme end of the toe, substantially as described.

35 2. An interior gage for fitting shoes em-

bracing in combination a thin flat flexible member of a length corresponding to the inside length of the shoe, and a toe gaging member projecting upwardly from the longitudinal member in position to be interposed between the extreme toe portion of the shoe and the toe of the inserted foot, substantially as described. 40

3. An interior gage for shoes embracing a member of thin flexible material adapted 45 to lie longitudinally inside the shoe, and a toe member located at the forward end of the longitudinal member in position to occupy the toe of the shoe, and having a transverse rear face for gaging the position of 50 the toe of an inserted foot.

4. An interior gage member comprising a strip of flexible material adapted to rest longitudinally on the bottom of the shoe, and a toe-filling member detachably secured 55 to the forward end thereof and forming an accurate spacing means between the end of the great toe and the extreme end of the shoe, substantially as described.

5. An inside gage for determining the 60 proper length of shoe comprising essentially a toe piece adapted to fit into the tip of the toe portion of the shoe and a thin flexible strip extending rearwardly therefrom so as to lie between the sole of the foot and the in- 65 sole of the shoe when the shoe is on the foot, substantially as described.

In witness whereof, I have subscribed the above specification.

ELMER J. BLISS.
